ABSTRACT OF THE DISCLOSURE

Method of forming design stitches in courses of a flat knitted fabric by individually transferring the stitches in groups of wales in opposite directions from the wales in which the stitches are originally formed to other wales in the groups.

This invention relates to flat selvaged fabric blanks and more particularly to a method of forming cable stitch patterns in such fabric blanks, the present application being a continuation-in-part of my application Ser. No. 552,334, filed May 23, 1966, as to all subject matter common thereto.

It is an object of the invention to provide a method of forming cable stitch patterns in fabric blanks knitted on full-fashioned knitting machines with a lesser number of operations of the transfer points then required in my said prior application.

Another object of the invention is the provision of a method of knitting flat fabric blanks on full-fashioned knitting machines in which stitches initially formed on groups of needles are individually transferred in opposite directions to other needles of the groups to produce cable stitch patterns in the fabric blanks.

With these and other objects in view which will become apparent from the following detailed description of the illustrative embodiments of the invention shown in the accompanying drawings, the invention resides in the novel fabric and in the method of making the same, as herein-after more particularly pointed out in the claims.

In the drawings:

FIG. 1 is a diagrammatic view of the stitch formation of one form of fabric made in accordance with the invention;

FIG. 2 is a view similar to FIG. 1 showing another form of fabric made according to the invention;

FIG. 3 is a view diagrammatically illustrating the sequence of steps required in forming the design stitch courses of FIGS. 1 and 2; and

FIG. 4 is a view similar to FIG. 3 illustrating a modified sequence of steps required in forming the design stitch courses of FIGS. 1 and 2.

Referring to FIGS. 1 and 2 there is shown portions of fabrics having cable stitch patterns according to the invention which are adapted to be knitted on bearded needles 10 of the machine of said application Ser. No. 552,334. In the fabric of FIG. 1 the cable stitches are shown formed by a single transfer point 9 in a series of five-needle stitch wales which are initially knitted on a group of five of the needles indicated at 10a, 10b, 10c, 10d and 10e in FIG. 3. The group of needles is flanked at opposite ends by dummy or non-knitting needles 11, from which the beards are removed, around which yarn is measured by the sinkers of the machine to provide additional yarn for the cable stitches and to form a wide wale 12 between the cable stitch wales and the wales of the adjacent plain stitch portions of the fabric knitted on adjacent needles 10 of the machine. The fabric courses in which the cable stitches are formed, indicated at 15,

are shown separated by three plain stitch courses 16.

Each of the courses 15 is formed by the sequence of steps indicated at A to H during which the single point 9 is initially aligned with the group of needles 10a to 10e from which the stitches are to be removed and then shifted to transfer the stitches to other needles of the group by the means and in the manner set forth in said application Ser. No. 552,334. Following knitting of the course of stitches as indicated in step A the single point 9 is initially positioned in alignment with needle 10e, as indicated in dotted outline in step B. After the stitch on the needle 10e is removed by the point, the point is shifted one needle to the left to transfer the stitch to needle 10d to double it with the stitch knit by needle 10d to complete step B. In step C the point 9 is aligned with needle 10b and following removal of the stitch on needle 10b, the point is shifted three needles to the right to transfer the stitch thereon to needle 10e. During step D the point is aligned with the needle 10c and following removal of the stitch on needle 10c the point is shifted one needle to the left to transfer the stitch thereon to needle 10b. During step E the point is aligned with needle 10d. Following removal of the doubled stitches from needle 10d, the point is again shifted one needle to the left to transfer the doubled stitches thereon to the needle 10c.

In step F the point is aligned with needle 10a and following the removal of the stitch on needle 10a, the point is shifted three needles to the right to transfer the stitch thereon to needle 10d. During step G the point 9 is aligned with the needle 10b. Following removal of the stitch on needle 10b the point is shifted one needle to the left to transfer the stitch thereon to needle 10a. In the step H the point is aligned with needle 10c and after removal of the doubled stitches on needle 10c the point is shifted one needle to the left to transfer the stitches on the point to needle 10b to complete the course 15. Following the last stitch transferring operation to complete the step H, the stitch initially formed by needle 10c is on needle 10a, the stitches initially formed by needles 10d and 10e are on needle 10b and the stitches initially formed by needles 10a and 10b are on needles 10d and 10e, respectively.

In the fabric of FIG. 2, the cable stitch courses 15 alternate with cable stitch courses 20. The courses 15 are formed by the steps A-H of FIG. 3 and the courses 20 are formed by similar steps except that where certain of the stitches in course 15 are transferred in single-needle movements to the left and other of the stitches are transferred in three-needle movements to the right, the transfer movements of the stitches in courses 20 are reversed so that certain of the stitches are transferred to the right in single-needle movements and others of the stitches are transferred to the left in three-needle movements.

FIG. 4 illustrates the sequence of steps required in forming the cable stitch pattern of FIG. 1 on a so-called half gauge machine adapted to knit very coarse fabric. In the half gauge machine alternate needles 10 are replaced by dummy or non-knitting needles 11 of the type employed to form wide wales 12 in the fabric of FIGS. 1 and 2 and around which yarn is measured by the sinkers of the machine to provide additional yarn for the coarse stitches formed by the needles 10, as set forth in said application Ser. No. 552,334. As shown in FIG. 4 the cable stitch pattern is formed on a group of five knitting needles 10f to 10j which alternate with non-knitting needles 11 and the end needles 10f and 10j of the group are separated from adjacent needles by two of the non-knitting needles.

The sequence of steps to form a cable stitch course similar to course 15 of FIGS. 1 and 2 on the half gauge machine are indicated at J to S with step J illustrating the

course as it is initially formed by the needles. Following knitting of the course of stitches of step J the point 9 is aligned with needle 10j, as indicated in dotted outline in step K. After the stitch on needle 10j is removed by the point it is shifted to the left to transfer the stitch to the needle 10i to double it with the stitch initially knit by needle 10i to complete step K. In step L the point, as indicated in dotted outline, is aligned with needle 10g and after removal of the stitch on needle 10g the point is shifted to the right to transfer the stitch to the non-knitting needle 11 intermediate the needles 10h and 10i.

During step M the point is again aligned with the non-knitting needle 11 between needles 10h and 10i and after removal of the stitch from the non-knitting needle the point is shifted to the right to transfer the stitch to needle 10j. In step N the point 9 is aligned with needle 10h and after removal of the stitch on needle 10h, the point is shifted to the left to transfer the stitch to needle 10g. In step O the point is aligned with the needle 10i. After removal of the doubled stitches from needle 10i, the point is shifted to the left to transfer these stitches to needle 10h. In step P the point is aligned with the needle 10f and after the stitch on needle 10f is removed the point is shifted to the right to transfer the stitch to the non-knitting needle 11 intermediate needles 10g and 10h. During step Q the point is again aligned with the non-knitting needle intermediate needles 10g and 10h and after the stitch is removed from the non-knitting needle, the point is shifted to the right to transfer the stitch thereon to needle 10i.

In step R the point is aligned with needle 10g and after removal of the stitch from needle 10g the point is shifted to the left to transfer the stitch to needle 10f. In step S the point is aligned with needle 10h and after removal of the doubled stitches from needle 10h the point is shifted to the left to transfer these stitches to needle 10g to complete the cable stitch course. Following the last stitch transferring operation of step S the stitch initially formed by needle 10h is on needle 10f, the stitches initially formed by needles 10i and 10j are on needle 10g and the stitches initially formed by needles 10f and 10g are on needles 10i and 10j, respectively.

Where it is desired to also form courses similar to courses 20 of FIG. 2 on the half gauge machine, the transfer movements of the point in steps K to S are reversed so that the stitches transferred to the left in FIG. 4 will be transferred to the right and those stitches transferred to the right in FIG. 4 will be transferred to the left.

The instant invention provides a method of forming a cable stitch pattern in fabric knitted on the needles of a full-gauge knitting machine with a single transferring point in seven transferring steps and on the needles of a so-called half-gauge machine in nine transferring steps as compared with the eight step method required in the full-gauge machine and the ten step method required for half-gauge machine as disclosed in said application Ser. No. 552,334. The invention also provides a method of forming the cable stitch pattern with a reduced number of transferring steps as compared to other known methods in which a single point is employed.

It will be understood that the improvements specifically shown and described by which the above results are obtained, can be changed and modified in various ways without departing from the invention herein disclosed and hereinafter claimed.

What is claimed is:

1. The method of forming design stitches in a flat fabric comprising the step of, forming a course of stitches of said fabric on knitting needles of a knitting machine, and the steps of individually transferring the stitches formed on a group of five of said needles to form said design stitches in said course, comprising transferring a stitch formed by a first knitting needle at one side of said group in one direction to the second knitting needle of said group to double it with a stitch formed by said second knitting needle, and manipulating said doubled stitches on

said second knitting needle and the stitches initially formed by the third, fourth and fifth knitting needles of said group in a sequence to transfer said stitch on said fourth knitting needle to said first needle, to transfer said doubled stitches on said second needle to said fourth needle, to transfer said stitch on said fifth needle to said second needle, and to transfer said stitch on said third needle to said fifth needle.

2. A method according to claim 1 in which said transfer of said stitch from said fourth needle to said first needle and said stitch from said fifth needle to said second needle are in three-needle transferring steps, and said transfer of said stitch from said third needle to said fifth needle and said doubled stitches from said second needle to said fourth needle are in one-needle transferring steps.

3. A method according to claim 2 in which said transfer of said stitch from said fourth needle to said first needle and said stitch from said fifth needle to said second needle are each in one of said three-needle transferring steps, and said transfer of said stitch from said third needle to said fifth needle and said doubled stitches from said second needle to said fourth needle are each in two of said one-needle transferring steps.

4. A method according to claim 1 in which said transferring steps include a first step to transfer said stitch on said first needle to said second needle to double it with said stitch on said second needle, a second step to transfer said stitch on said fourth needle to said first needle, a third step to transfer said stitch on said third needle to said fourth needle, a fourth step to transfer said doubled stitches from said second needle to said third needle, a fifth step to transfer said stitch on said fifth needle to said second needle, a sixth step to transfer said stitch from fourth needle to said fifth needle, and a seventh step to transfer said doubled stitches from said third needle to said fourth needle.

5. A method according to claim 4 in which there is a non-knitting needle intermediate the end knitting needles of said group and the other knitting needles forming stitches in said course, said non-knitting needle forming a wide wale intermediate the ends of said design stitches formed on said group of knitting needles and said stitches formed by said other knitting needles.

6. A method according to claim 2 in which said group of needles includes five knitting needles for forming stitches of said course alternating with non-knitting needles, and said transfer of said stitch from said fourth knitting needle to said first knitting needle and said stitch from said fifth knitting needle to said second knitting needle are in transferring steps equal to three of said knitting and non-knitting needles, and said transfer of said stitch from said third knitting needle to said fifth knitting needle and said doubled stitches from said second knitting needle to said fourth knitting needle are in transferring steps equal to two of said knitting and non-knitting needles.

7. A method according to claim 6 in which said transfer of said stitch from said fourth knitting needle to said first knitting needle and said stitch from said fifth knitting needle to said second knitting needle are each in two of said three-needle transferring steps, and said transfer of said stitch from said third knitting needle to said fifth knitting needle and said doubled stitches from said second knitting needle to said fourth knitting needle are each in two of said two-needle transferring steps.

8. A method according to claim 7 in which said stitch on said fourth knitting needle and said stitch on said fifth knitting needle are transferred to a non-knitting needle during one of said three-needle transferring steps thereof.

9. The method of forming design stitches in a flat fabric comprising the step of forming a course of stitches of said fabric on knitting needles of a knitting machine, and the steps of individually transferring the stitches formed on a group of five of said needles to form said design stitches in said course, comprising first transferring a stitch formed on one of the two needles on one side of said

group a distance of one needle toward the other side of said group to double it with a stitch formed by the adjacent needle to which it is transferred, then secondly transferring a stitch formed on one of the two needles on the other side of said group over a plurality of needle distances to the needle of the one side of said group from which said first transfer was effected, continuing to transfer stitches from said group of needles a distance of one needle in the direction of said first transfer and a distance of said same plurality of needles in the direction of said second transfer until the stitches initially formed on the two needles of said one side are located on one of said two needles on the other side, the stitches initially formed on the two needles on said other side are located on the two needles of said one side, and the stitch initially formed on the middle needle of said group is located on one of the two needles of said other side.
